(57) **CLAIM**

The ornamental design for an under hood service tray, as shown and described.

DESCRIPTION

This application is related to a co-pending U.S. utility application entitled Under Hood Service Tray filed on Sep. 4, 2009 and assigned U.S. Ser. No. 12/584,391, and which is incorporated herein by reference.

FIG. 1 is a perspective view of the under hood service tray according to a first embodiment of the present design; FIG. 2 is a right side elevation view of the under hood service tray as shown in FIG. 1;

FIG. 3 is a left side elevation view of the under hood service tray as shown in FIG. 1;

FIG. 4 is a front elevation view of the under hood service tray as shown in FIG. 1;

FIG. 5 is a rear elevation view of the under hood service tray as shown in FIG. 1;

FIG. 6 is a top plan view of the under hood service tray as shown in FIG. 1;

FIG. 7 is a bottom plan view of the under hood service tray as shown in FIG. 1; and,

FIG. 8 is a perspective view of the under hood service tray, as shown in FIG. 1, in relation to a raised automobile hood. The broken lines in FIG. 8 setting forth a portion of a car body are for illustrative purposes only and form no part of the claimed design.
